Inventor:
Henry L. Carpenter
By Paul & Hawley, attorneys.

UNITED STATES PATENT OFFICE.

HENRY L. CARPENTER, OF MINNEAPOLIS, MINNESOTA.

STOCKING-SUPPORTER.

SPECIFICATION forming part of Letters Patent No. 547,846, dated October 15, 1895.

Application filed October 17, 1894. Serial No. 526,191. (No model.)

To all whom it may concern:

Be it known that I, HENRY L. CARPENTER, of Minneapolis, county of Hennepin, State of Minnesota, have invented a new and Improved Stocking-Supporter, of which the following is a specification.

My invention relates to stocking fasteners or supporters designed to take the place of the various kinds of garters now in vogue.

10 The object of my invention is to provide a supporter in the form of a small clasp adapted to grip the stocking and some near part of the under-clothing, thereby avoiding the use of elastics, which are often injurious to the health 15 and detract from the comfort of the wearer.

To this end my invention consists in a metal clasp or gripping device having at its opposite ends pairs of jaws, the pairs being at right angles to each other.

20 My invention consists, further, in a locking device provided in connection with one of the jaws to lock the other, and, further, my invention consists in the particularly simple and economical construction of the clasp and 25 in combinations of parts, all as hereinafter described, and particularly pointed out in the claims.

The invention will be more clearly understood by reference to the accompanying drawings, forming part of this specification, and in which—

30 Figure 1 shows a device embodying my invention and the manner of applying the same. Fig. 2 is an enlarged perspective view of the 35 supporter. Fig. 3 is a view of the lower end of the same. Fig. 4 is a sectional view on the line *x x* of Fig. 3. Fig. 5 is a view of the inner or larger plate alone. Figs. 6 and 7 are top and sectional views showing another 40 form of locking device.

In the drawings the clasp is shown to be made up of a plate 2 and a pivoted jaw-lever 3, practically forming a part thereof, and an upper plate 4, hinged on the lower plate 2. 45 The plates 2 and 4 have the inwardly-turned and preferably serrated lower ends forming the gripping-jaws 5 and 6, which grasp the upper part of the stocking-leg. The jaw-lever 3 is provided with teeth on its inner side, and 50 the part of the plate 2 opposite the jaw-lever is also serrated, between which and the jaw-lever a portion of the under-clothing is placed.

The opposite end 7 of the jaw-lever projects outwardly beyond the plate, and by pressing in upon this projection the other end of the 55 jaw-lever will move away from the part of the plate 2 forming the other jaw. The plate 4 is provided with downwardly-extending lugs 8, which overlap and are pivotally connected to similar lugs 9, extending upwardly from the 60 plate 2. A pin 10 is passed through the overlapping lugs from one side of the device to the other and forms the pivotal connection between the upper and lower plates. A spring 11 is wound around the pin 10 and has one 65 end bearing against the under side of the plate 4, while the other end extends out over the jaws 5 and 6 and has its end secured under a lip or projection 12 thereon. The projecting end 7 of the jaw-lever 3 has an inwardly- 70 turned extension 13, which laps over the edge of the plate 4 when a portion of the under-clothes has been placed between the jaw-lever 3 and the portion of the part 2 forming the other jaw, and thereby forms a lock prevent- 75 ing the jaws 5 and 6 from separating while the device is in use. Another locking device is shown in Figs. 6 and 7, in which the plate 4 is provided with an opening 14, through which the end of a stud 15, secured to the 80 jaw-lever 3, is arranged to pass when the jaws 5 and 6 are separated when the device is not in use. When in use, the upper end of the stud 15 will be moved away from beneath the opening 14 in the upper plate 4, so that the 85 jaws 5 and 6 cannot be separated until the jaw-lever 3 is disengaged from the under-clothing and returned to its normal position.

It is obvious that the device may be varied considerably in the details of its construction 90 without departing from the spirit of my invention.

Having thus described my invention, I claim as new and desire to secure by Letters Patent—

95 1. A stocking supporter consisting of a double jawed fastener wherein the pairs of jaws are at right angles to one another yet in the same or parallel planes and means in connection with one jaw for locking the other, 100 whereby the latter will be tightly closed, substantially as described.

2. A stocking supporter, consisting of a double clasp having two pairs of jaws, and

means in connection with one pair of jaws for locking the other pair, and said locking mechanism being arranged to permit the simultaneous closing of both pairs of jaws when the 5 supporter is in use, substantially as described.

3. A stocking supporter, consisting of the plates pivoted upon one another and having their engaging ends provided with jaws or clamping edges, one of the plates being cut 10 away at the opposite end, a pivoted lever having an end within the space, the adjacent edges of said lever or plate serving as jaws, and a spring pressing said lever against said edges, substantially as described.

15 4. A stocking supporter, consisting of the plates pivoted upon one another and having their engaging ends provided with jaws or clamping edges, one of the plates being cut away at the opposite end and a pivoted lever 20 having an end to fill the space, the adjacent edges of said lever or plate serving as jaws, a spring pressing said lever against said edges, and a locking device on said lever to engage said second plate, substantially as described.

25 5. The combination in a stocking supporter of the two plates pivoted upon one another and having their engaging ends provided with clamping jaws, one of said plates having a clamping edge at its opposite edge and at 30 right angles to the other, a lever pivoted on

said plate and having a corresponding clamping edge, and a single spring adapted to operate said plates and said lever, substantially as described.

6. A stocking supporter, consisting of a 35 lower plate, provided with the pivoted jaw lever 3 forming one side of the jaws in the end of said plate, said lower plate being provided with a clamping edge at one end, a second plate pivoted upon said lower plate and 40 also provided with a clamping edge to engage the edge of said lower plate, and said part 3 being provided with a part 7 extending laterally from between the two plates for moving one of the jaws, substantially as described. 45

7. A stocking supporter, consisting of a lower plate, the pivoted jaw lever 3 in substantially the same plane with said plate and forming with one edge thereof a clamping jaw, and said lower plate being also provided 50 with a clamping edge at one end, a second plate pivoted upon said lower plate and also having a clamping edge to engage the edge of said lower plate, for the purpose set forth.

In testimony whereof I have hereunto set my hand this 9th day of October, A. D. 1894.

HENRY L. CARPENTER.

In presence of—

FREDERICK S. LYON,

A. C. PAUL.
